UNITED STATES PATENT OFFICE.

THOMAS D. BAUSHIER, OF READING, PENNSYLVANIA.

FUEL-CARTRIDGE.

969,151.

Specification of Letters Patent. Patented Sept. 6, 1910.

Application filed January 10, 1910. Serial No. 537,300.

To all whom it may concern:

Be it known that I, THOMAS D. BAUSHIER, citizen of the United States, residing at Reading, in the county of Berks and State 5 of Pennsylvania, have invented certain new and useful Improvements in Fuel-Cartridges, of which the following is a specification.

This invention relates to a new article of 10 manufacture in the form of a fuel cartridge and the object in the present invention is to provide a device in the form of a container for a specially prepared fuel.

The device consists of a cylindrical, elastic body filled with fuel, and so made that the outside atmosphere will have access to the fuel at all points, to insure the free consumption of the fuel.

The invention is more fully set forth in 20 the following specification and clearly illustrated in the accompanying drawing, in which:—

Figure 1 shows my cartridge complete. Fig. 2 shows the cylinder before being 25 filled.

The device consists of a cylindrical body portion 1, made of a series of loosely woven wire strands, thus permitting a certain longitudinal elasticity.

The one end 2, of the body is semi-spherical and is closed and the opposite end, through which the cylinder is filled, is normally open but after being filled, is closed by bringing together the ends 3 of 30 the wire strands and twisting them together, or, if preferred, these ends when so brought together may be secured by means of a binder 4. The closed end is semi-spherical in form, so that it may be easily 40 entered in a space of limited dimensions. If the end were formed with corners or if the opposite end were inserted, it would likely strike some obstruction and interfere with its entrance.

The cylinder is filled with particles of combustible material, loosely arranged therein, so as to permit the cylinder to be drawn out to a length that will reduce its diameter sufficiently to permit its entrance into spaces of varied dimensions. These 45 particles of fuel are of varied sizes, so that while there will remain air spaces surrounding the particles, assuring free access of air, yet substantially the entire capacity of the cartridge is utilized as the smaller particles 50 will find room in the spaces between the larger particles.

It is evident that both ends may be left open, in the manufacture of the cylinders, to be closed after filling, as is the one end in 55 the device just described.

It is also evident that the size of wire used and the size of the mesh formed thereby may be varied to suit different sizes of fuel 60 particles and conditions.

Having thus fully described my invention, what I claim and desire to secure by Letters Patent is:—

A longitudinally elastic fuel cartridge of cylindrical form, made of a series of loosely 70 woven wire strands forming an open mesh, the free ends of said wire strands being located at the open end, said cartridge being closed at one end which closed end is semi-spherical in form, and whose open end 75 may be closed by joining together the free ends of the wire strands, a binder for tying said free ends together in closed position and a filler composed of combustible fuel particles of varied sizes.

In testimony whereof I affix my signature, in presence of two witnesses.

THOMAS D. BAUSHIER.
